UNITED STATES PATENT OFFICE.

JOSEPH E. FIELDS, OF BRADLEYVILLE, MISSOURI.

RAILWAY-GATE.

1,182,667.

Specification of Letters Patent.

Patented May 9, 1916.

Application filed May 17, 1915. Serial No. 28,702.

To all whom it may concern:

Be it known that I, JOSEPH E. FIELDS, a citizen of the United States, and a resident of Bradleyville, in the county of Taney and 5 State of Missouri, have invented certain new and useful Improvements in Railway-Gates, of which the following is a specification.

My invention relates to improvements in railway gates, and it consists in the combinations, constructions, and arrangements 10 herein described and claimed.

An object of my invention is to provide a safety device for the crossing which may be so operated on the approach of a train that 15 the crossing cannot be used.

A further object of my invention is to provide a device of the type described in which a safety device is provided for obstructing the roadway so that the user of the 20 crossing cannot cross the track, but which will permit him to pass the obstruction if by chance he should be on the track.

Other objects and advantages will appear in the following specification, and the novel 25 features of the invention will be particularly pointed out in the appended claims.

My invention is illustrated in the accompanying drawings forming part of this application in which—

30 Figure 1 is a plan view of a track equipped with my invention. Fig. 2 is an enlarged detail plan view of a portion of the device. Fig. 3 is a section along the line 3—3 of Fig. 4. Fig. 4 is a section along the line 4—4 of Fig. 2. Fig. 5 is a section along the line 5—5 of Fig. 1. Fig. 6 is a section on the line 6—6 of Fig. 1.

This invention is designed to be applied to any ordinary railway system. In Fig. 1 40 I have shown such a system having the track rails 1 and 2. At 3 I have shown a highway crossing. Disposed along the inner edges of the track rails 1 and 2, are movable members which I have designated in general by 45 4. These consist of plates having upwardly extending side flanges 4^a. The plates are also provided on their under side with downwardly extending members 8 of substantially U-shaped form as shown in Fig. 4. Leaf springs 5 are secured to the ties 6, the springs being arranged to support the plates 4 normally in an upper position. Secured to the ties are L-shaped brackets 7 through which extend pins 9 (see Fig. 9) 55 one end of each pin being bent upwardly and secured to the plate 4. A spiral spring

10 is disposed between the brackets 7 and the bent end of the pin. The action of this spring is to keep one end of the plate normally close to the inner edge of the track rail. At the ends of each of the plates 4 is secured a flexible member, such as a wire or cable 11, which will permit a slight vertical movement of the plate and also a lateral movement. The wire or cable, as will be 60 seen from Fig. 4, is secured to the tie.

As will be seen from Fig. 2, the plates 4 are held normally in an inclined position with respect to the track rails 1 and 2. This is accomplished by providing springs 10 at 70 one end of the plate 4 which are strong, while the other springs toward the opposite end of the plate are weaker, so that the normal position of the plate will be that shown in the figure. It will also be observed that 75 some of the springs including those between the ends of the plates 4 are connected directly to the plates and also to the brackets 7 and do not have the pins 9.

At each side of the track, the crossing 80 3 is provided with an inclined approach 3^a, see Fig. 5. At the bottom of this inclined approach is disposed a hinged plate 12 which extends across the highway, this plate being supported upon any suitable material 85 which will prevent the plate from sticking to the material in wet weather. As a further precaution to keep the under surface of the plate 12 in a dry condition, I provide a central supporting member 13 on each side 90 of which are culverts 14 for permitting the passage of water.

As will be seen from the drawing, there may be two or more sets of movable plates 4 on each side of the crossing. At a certain 95 position on the track, I secure the end of a rod or chain. One of these securing members is shown at 15 in Fig. 1. This connects with a chain or cable 16 which passes through the lower portion of the U-shaped 100 members 8, slots being provided for this purpose. In Fig. 1, this chain 16 is shown as passing around a pulley 17 and being attached to a spring which in turn is attached to a cable or wire 19, the spring and wire 105 being preferably disposed in a conduit 20 (see Fig. 5) and one end of the wire 19 being secured to a lever 21 which is pivoted at 22 and whose opposite end bears on the under side of the plate 12. It will be seen 110 from Fig. 1, that at each highway there are four of these levers 21. Thus, if a train is

approaching in either direction, the plates 12 on each side of the track, will be separated.

From the foregoing description of the various parts of the device, the operation thereof may be readily understood. Let us assume that a train 26 is approaching on the track from the right hand side of Fig. 1. Normally the parts are in the position shown in Figs. 1 and 2, but when the flange 25 of the wheel 24 reaches the plate 4, it will push it downwardly into the position shown in dotted lines in Fig. 4, thereby exerting tension on the chain 16. This tension will be transmitted to the spring 18, and by means of the rod or wire 19, to the lever 21, thereby causing the raising of the plates 12 into the position shown in full lines in Fig. 5, the chain 27 serving as a means for limiting the movement of the plates. The plates 4 on the opposite side of the track will be operated in a similar manner and will cause the raising of the plate 12 so that the track will be guarded from both sides. It will be noted that the plate 12 is raised to such a height that the wheels 28 of a vehicle approaching the plate as shown in Fig. 5, cannot surmount the plate. When the driver of the vehicle sees the plates in raised position, he will therefore stop, but even if he attempts to proceed, the plates will prevent crossing the track. If the driver of the vehicle should have passed one of the plates 12 in crossing the track, all he needs to do is to keep on, because the plate 12 on the opposite side of the track is not raised so high that the horses if driven to it, could not get over the obstruction. Furthermore, when the wheels of the vehicle reach the plate 12 on the opposite side, they will press the latter downwardly, the springs 18 yielding to permit the plate to lower, thus permitting the vehicle to pass. The same is true of an automobile or other similar self-propelled vehicle. When the vehicle has crossed, these springs will retract the plate into its danger position. As many or as few of these movable members 4 may be employed on a track as desired, but it is advisable to use a sufficient number to insure the safety of the crossing. It will be apparent that they should be near enough together so that the front part of the train should reach one before the rear part leaves another. Furthermore, these members 4 should be made of such a length that they will extend from the front wheels of a car to the rear wheels, so that during the passage of the train, the plate 12 shall not drop. Immediately after the train has passed, the springs 5 force the plates 4 up into their

normal position, thus permitting the plates 12 to resume their original positions through the action of gravity. Now consider the action on the opposite side of the crossing, that is to say, after the train has passed the crossing. It will be noted that the members 4 are inclined oppositely to the members 4 on the right hand side of the crossing. The flanges of the wheels now enter behind the flanges 4^a of the plates 4, and simply push the plates inwardly but not downwardly, so that after the train has passed the crossing, the plates 12 will not be affected. If, however, the train is coming from the left of Fig. 1, then the flange will engage the members 4 to push them downwardly so as to operate the plates 12. In Fig. 3 I have shown the pushing down of the plate 4 by means of a flange 25 on the wheel 24, while in Fig. 9 I have shown the flange 4^a of the plate 4 being pushed inwardly so as to permit the passage of the flange 25 of the wheel between the plate 4 and the rail 22.

I claim:

1. The combination with a railway track having a crossing, of a hinged plate disposed across the crossing approach and constituting a portion thereof, said plate being adapted to move so as to present an upturned edge to one approaching the railway track, and means carried by the track for raising the plate into its upper obstructing position on the passage of a train, said last named means comprising a flanged plate disposed along the track rails and having downwardly projecting portions, a flexible member connected with said downwardly projecting portions, and a spring having operative connection with said crossing obstructing plate at one end and with the said flexible member at the other end.

2. The combination with a railway track having a crossing, of a hinged plate disposed across the crossing approach and constituting a portion thereof, a pivoted arm disposed underneath said hinged plate and having one end in sliding engagement with said plate, said plate being adapted to be moved so as to present an upturned edge to one approaching the railway track, a movable plate disposed along the track rails and having downwardly projecting portions, a flexible member connected with said downwardly projecting portions, and a spiral spring having operative connection with said pivoted arm at one end and with said flexible member at the other end.

JOSEPH E. FIELDS.
